PORTABLE RAIL GRINDING MACHINE

Samuel R. Oldham, Chicago, and Frank C. Hasse, La Grange, Ill., assignors to The Oxweld Railroad Service Company, a corporation of Delaware

Application January 10, 1929. Serial No. 331,521

5 Claims. (Cl. 51—178)

This invention pertains to portable grinding machines and more specifically to such a machine especially adapted for grinding the repaired tread of used railroad rails.

When in service railroad rails wear more rapidly at the ends than at intermediate portions and, consequently, need to be replaced when all but the ends are in condition to give satisfactory service for a long period of time. In order to prolong the life of such rails the worn ends are built up with metal added by a fusion welding process and then the added metal is ground down to the original contour line of the rail. On electric roads this grinding is usually done by an emery wheel held in the hands of a workman and driven through a flexible shaft by an electric motor which draws its current from the road's distributing system. This method of grinding is slow as it is difficult for an operator to hold an emery wheel rigid enough to fully utilize its cutting ability, and the results obtained are of inferior quality as it is difficult to manipulate a wheel such as usually used for this class of work. While rails on railroads that are not electrified may also have their life prolonged by the same treatment, the process is not used as frequently on such roads due to the lack of a convenient power supply along the line.

Therefore, one object of this invention is to provide a portable rail grinding machine adapted for use on all railroads regardless of whether they are electrified or not. Another object is to provide a portable grinding machine having an abrasive that cuts rapidly and is not liable to fly apart and injure an operator. Another object is to provide a portable grinding machine that will rigidly support an abrasive so its cutting qualities may be utilized to the full extent of their ability. Another object is to provide a portable grinding machine that will produce a smooth surface without the exercise of unusual skill in its operation. Another object is to provide a portable grinding machine having a single source of power for driving the abrasive and for propelling the grinding machine along a railroad track. Other aims, objects, and novel features, will be apparent from the drawings and from the following description.

The above aims and objects of the present invention are attained by the mechanism shown in the accompanying drawings, in which;

Fig. 1 is a reduced side elevation of our improved portable grinding machine showing the general arrangement of its component parts;

Fig. 2 is a reduced plan view of the supporting

means for the abrasive which is shown in operative position over one rail of the track on which the grinding machine is resting;

Fig. 3 is a reduced side elevation of the supporting means for the abrasive with portions thereof cut away to show its construction;

Fig. 4 is a reduced elevation of the outer end of the supporting means for the abrasive with portions thereof cut away to show the carriage operating mechanism;

Fig. 5 is a section along the line 5—5 of Fig. 4 looking in the direction of the arrows, and;

Fig. 6 is a section along the line 6—6 of Fig. 3 looking in the direction of the arrows.

The portable rail grinding machine shown in the drawing may comprise abrading means A such as an abrasive disk, carried by supporting means B in the form of a swinging arm, that is hinged to the transporting means C which may be a railroad track car, and rotated by a driving means D such as the gasoline engine that propels the car along the railroad track on which it is adapted to run.

The abrading means A may be an abrasive disk 10 such as those made by C. H. Besley & Company, of Chicago, Ill., and composed of an abrasive grain such as corundum or emery attached to a cloth backing by a suitable bond or adhesive. Such abrasive disks cut rapidly and are not liable to become broken and fly apart under severe conditions of service, abuse, or accident, and injure the grinding machine operator or some other person who may be nearby. The abrasive disk 10 is cemented to a suitable metal supporting disk 11 by one of the cements made by the said C. H. Besley & Company for that purpose and well known in the arts and trades. Upon the upper side of the metal disk 11 is a hub 12 by means of which the disk 11 is threaded to a vertical spindle 13 forming part of the supporting means B.

The supporting means B may comprise a vertical spindle 13 carried by a sliding carriage 14 by means of the roller bearings 15 and 16 in which the spindle 13 is free to rotate. The carriage 14 is attached to the outer end of a swinging arm 17 by the gib 18 so it is free to slide up or down thereon. The gib 18 may be an integral part of the arm 17 or it may be a separate part attached to the arm 17 by the bolts 18'. Attached to the front of the gib 18 by means of the screws 19 are two racks 20 and 21 which are located so one rack is at each side of the carriage 14. Attached to the right side of the carriage 14 by the screw 22 is a pinion 23 that meshes

with the rack 21 and carries an outwardly extending tube 24 to which the operating handles 25 are attached and by which the pinion 23 is manually rotated to move the carriage 14 up and down. Attached to the left side of the carriage 14 is a pinion 26, similar to the opposed pinion 23, which meshes with the rack 20 and also carries an outwardly extending tube 27 to which the operating handles 28 are attached. One of the pinions 23 and 26, and the rack 20 or 21 with which it meshes, may be dispensed with for the sake of economy as the duplication of racks, pinions, and handles, is to make the operation of raising and lowering the carriage 14 and the abrasive disk 10 more convenient for the person operating the grinding machine. The spindle 13 extends upward some distance above the top of the carriage 14, and mounted on this portion of the spindle 13 with a loose sliding fit is a pulley 29 which is held so it rotates with the spindle 13 by the key 30 which is secured to the spindle 13 and slides in a keyway in the pulley 29. A guard 31 is secured to the gib 18 by the machine screw 32 so it extends upward past the pulley 29 where it makes a right angle turn and extends across the upper face of the pulley and terminates in a bifurcated end 33 that partially surrounds the spindle 13 just above the upper end of the hub 34 of the pulley 29. Another portion of the guard 31 extends along the lower face of the pulley 29 and terminates in a bifurcated end 35, similar in form to that of 33, which partially surrounds the spindle 13 just below the lower end of the hub 34 of the pulley 29. The guard 31 holds the pulley 29 in a substantially fixed vertical position with relation to the arm 17 when the carriage 14 is moved up and down relative to the arm 17, and the spindle slides up and down in the pulley 29 and tends to carry the pulley along with it.

The inner end of the arm 17 is divided into upper and lower portions that terminate in bearings 36 and 37 that respectively surround cylindrical pivots 38 and 39 which extend in alignment upward and downward respectively from the gear box 40 so the movable arm 17 is secured to the stationary car and gear box 40 by a vertical pivot.

The driving means D may comprise a gear box 40 having a vertical shaft 41 extending from within the gear box upward through the pivot 38 and carrying at its upper end a pulley 42 in such a position that it is in alignment with the pulley 29. The gear box 40 may also comprise a horizontal shaft 43 extending from within the gear box outward laterally and carrying at its outer end a pulley 44. Rigidly attached to the inner ends of the shafts 41 and 43 respectively are intermeshed miter gears 45 and 46 so related that when the shaft 43 is driven the shaft 41 rotates at the same speed. The gear box 40 may be substantially oil tight so it may be more or less completely filled with oil or grease to lubricate the gears 45 and 46 therein. It is understood, of course, that it is not imperative to employ miter gears to connect the shafts 41 and 43 as gears having a different ratio may be employed with equal facility or even with an added advantage where a different gear ratio is desirable. The gear box 40 may also have an attaching plate 47, which may be integral or otherwise, by means of which the gear box is secured to one end of the track car 48 by the bolts 49, substantially midway between the wheels. The transporting means C may comprise a track

car 48 of any kind that is light enough to be manually handled. It may have four wheels 50 adapted for running on the rails 51 of a railroad track, and a gasoline engine 52 adapted for propelling the car 48 along the railroad track. Such a car is made by the Buda Company of Harvey, Illinois, and is known as the No. 419 Buda Trackster. While the Buda Trackster is especially well adapted for assembly as a component part of the portable grinding machine described herein, other track cars may, however, be used.

The driving means D may also comprise the gasoline engine 52 having a pulley 53 on the outer end of its crank shaft and in alignment with the pulley 44 on the gear box 40. A horizontal belt 54 runs on the horizontal pulleys 44 and 53, and a vertical belt 55 runs on the vertical pulleys 29 and 42. The tension of the horizontal belt 54 may be varied by the idler pulley 56 which is carried by the arm 57, which, in turn is controlled by the adjustable hand lever 58 to press the pulley 56 against the belt 54 with various degrees of pressure. The idler pulley 56 and the hand lever 58 may be held in their various adjusted positions by a notched quadrant 59. A belt guard 31' may surround the belt 55 and be carried by the guard 31 and the arm 17.

As the arm 17 is pivoted to the track car 48 substantially midway between the rails upon which the car runs, it follows that when the surface of one of the rails is to be ground that the arm 17 must be swung to either one side or the other so the abrasive disk 10 is over the particular rail to be operated on. The arm 17 may be held in this operating position by an adjustable brace 110 rod 60. The outer end of the rod 60 is supported loosely in a sleeve 61 that is pivoted to the arm 17, and the inner end of the rod 60 is threaded in a nut 62 that is pivoted to a bracket 63, which in turn is attached to the end of the car 48 near one side by the screw 64. A stationary collar 65 rigidly attached to the rod 60 at one side of the sleeve 61, and a removable collar 66 attached to the rod 60 at the other side of the sleeve 61, keeps the rod from sliding endwise through the sleeve 61 but, at the same time provides a swivel connection, and permits the rod 60 to rotate in the sleeve 61 as it is screwed various distances in or out of the nut 62 to adjust the position of the arm 17 relative to the rail over which the abrasive disk 10 is positioned. The rod 60 extends outward beyond the sleeve 61 to a point approximately opposite the outer end of the arm 17, and attached to the outer end of the rod 60 is a crank 67 by which the rod may be conveniently rotated by the operator to adjust the position of the abrasive disk 10 over the rail.

When it is desirable to position the abrasive disk 10 over the opposite rail from that over which it is shown in Fig. 2, the rod 60 is unscrewed from the nut 62, and the collar 66 is removed from the rod 60 which is slid endwise out of the sleeve 61. Then the arm 17 is swung across the track so the abrasive disk 10 is over the opposite rail and the rod 60 is inserted in the sleeve 61 from the opposite side of the arm 17. The collar 66 is replaced on the rod 60 and the threaded end of the rod is screwed in the nut 62 which is secured to the car 48 in the same manner as the nut 62 only at the opposite side of the gear box 40.

By loosening or removing the belt 54 from the engine pulley 53 the moving parts of the grinding machine may be stopped, and then the machine may be propelled along the railroad

track on which it is used, by the gasoline engine 54 of the driving means D in the same manner as the track car 48 might be run if the means for grinding rails were not attached to it.

5 When the portable grinding machine is used to grind down or remove the surplus metal from a repaired portion of the upper surface or tread of a rail, the track car 48 is left on the rails of the railroad track and the arm 17 is swung to one side or the other so the abrasive disk 10 is positioned over the repaired portion of the rail to be ground, where it is secured by the brace rod 60 in the manner already described. If the belt 54 is not already on the pulley 53 it is placed there and the gasoline engine 52 is started. The idler pulley 56 is then adjusted by means of the hand lever 58 so the belt 54 has sufficient tension to drive the abrasive disk 10. Thus the engine 52 that is used to propel the track car 48 along the railroad track is also used to drive the abrasive disk 10, thereby overcoming the need of providing two separate sources of power.

When the abrasive disk 10 is driven by the gasoline engine 52, the engine power is transmitted to the disk by the following parts of the grinding machine in substantially the order named. From the engine pulley 53 through the belt 54, pulley 44, shaft 43, bevel gear 46, bevel gear 45, shaft 41, pulley 42, belt 55, pulley 29, spindle 13, hub 12, and supporting disk 11, to the abrasive disk 10.

With the abrasive disk 10 positioned over a repaired portion of the rail 51 on which the track car 48 is resting, the operation of grinding the surplus metal from the repaired portion is as follows. By manually manipulating one of the carriage control handles, such as 25, the pinion 23 is rotated so it rolls down the rack 21, with which it is in mesh, and forces the carriage 14 downward, which in turn carries the spindle 13 and the abrasive disk 10 with it, and thereby the abrasive disk 10 is brought into contact with the repaired portion of the rail. When grinding a flat surface, such as the tread of a rail, by a flat abrading surface, such as the abrasive disk 10, a certain amount of traverse motion is usually employed to increase the grinding speed and decrease the heat generated. This traverse motion may be imparted to the abrasive disk 10 by turning the handle 67 and screwing the rod 60 in and out of the nut 62, thereby swinging the arm 17 and the abrasive disk 10 back and forth across the rail, or the track car 48 may be slowly moved back and forth along the track by the operator.

Some of the unique results obtained by the novel construction and arrangement of the portable grinding machine shown and described herein are as follows. By employing a gasoline engine as a source of power the grinding machine may be used on any railroad regardless of whether it is electrified or not. If desirable on electrified roads the gasoline engine may be dispensed with and an electric motor used in its stead, or the gasoline engine may be used to propel the car along the track and an electric motor may be used to drive the abrading means.

The abrasive disk 10 is used as the abrading means on account of its rapid cutting qualities. While a cylindrical emery wheel might be used instead, the disks are preferred because they cut more rapidly, withstand a greater amount of abuse and, should they become broken and fly apart, they are so thin and light that the parts thrown off are not liable to seriously injure an operator if at all.

70 By employing the rigid arm 17 to support the

abrasive disk 10, and by employing a positive and powerful means of moving the carriage 14 to force the disk against the rail, the cutting qualities of the disk may be utilized to the fullest extent of their ability.

80 By using an abrasive disk that presents a flat surface to the rail, instead of a cylindrical surface such as that presented by an emery wheel, a smooth flat surface may be secured on the portion ground by the abrasive with the exercise of but little skill or experience on the part of the operator. In fact, with our improved grinding machine an unskilled operator may produce a smoother surface than a skilled operator could with a manually supported cylindrical emery wheel such as usually employed.

85 Furthermore, by arranging the grinding machine so a single source of power, such as the gasoline engine 52, propels the machine along the railroad track upon which it operates, and also drives the abrading means, such as the abrasive disk 10, by which the grinding operation is performed, the cost of the machine is reduced, its range of usefulness is increased, and duplication of expensive parts is avoided.

90 Various changes in the arrangement, alterations in the construction, and substitutions for the materials and elements, may be made in the grinding machine without departing from the invention or sacrificing any of the rights there- 105 under.

We claim:

1. In a portable rail grinding apparatus, a car, an arm pivotally supported at one end by said car and having its other end free for lateral swinging movement with respect to said car and to the surface to be ground, a revoluble tool-carrying spindle at the free end of said arm, means for vertically adjusting said spindle, and means connected with said arm and including a rod 110 axially adjustable with respect to said car for positioning said arm laterally with respect to said surface and for imparting a limited lateral movement to said arm when so positioned, thereby to shift the tool relatively to said surface. 120

2. In a portable rail grinding apparatus, a car, an arm pivotally supported at one end by said car and having its other end free for lateral swinging movement with respect to said car and to the surface to be ground, a revoluble tool- 125 carrying spindle at the free end of said arm, means for vertically adjusting said spindle, and means connected with said arm and including a rotatable rod normally axially fixed with respect thereto but axially adjustable with respect to 130 said car for positioning said arm laterally with respect to said surface and for imparting a limited lateral movement to said arm when so positioned, thereby to shift the tool relatively to said surface. 135

3. In a portable rail grinding apparatus, a car, an arm pivotally supported at one end by said car and having its other end free for lateral swinging movement with respect to said car and to the surface to be ground, a revoluble tool- 140 carrying spindle at the free end of said arm, means for vertically adjusting said spindle, and means including a rod connected with said arm by a swivel connection and having a screw-threaded connection with said car whereby said 145 arm may be laterally positioned with respect to said surface, said screw-threaded connections operable for imparting a limited lateral movement to said arm when so positioned to shift the tool relatively to said surface. 150

4. In a portable rail grinding apparatus, a car, an arm pivotally supported at one end by said car and having its other end free for lateral swinging movement with respect to said car and to the surface to be ground, a revoluble tool-carrying spindle at the free end of said arm, means for vertically adjusting said spindle, and a rotatable rod having a swivel connection with said arm and provided at one end with an operating handle and at its other end with a screw-threaded portion, complementary screw-threaded means carried by said car and cooperatively engaged with the screw-threaded portion of said rod, the connection of said rod with said arm and car providing a means whereby said arm may be laterally positioned with respect to said surface, and the screw-threaded connection of the end of said rod with the complementary means on said car providing for adjustment of said arm to shift the tool relatively to said surface.

5. In a portable rail grinding apparatus, a

car, an arm pivotally supported at one end by said car and having its other end free for lateral swinging movement with respect to said car and to the surface to be ground, a revoluble tool-carrying spindle at the free end of said arm, means for vertically adjusting said spindle, a swivel connection carried by said arm, a rod rotatably mounted in said swivel connection and normally axially fixed relatively thereto but capable of separation therefrom, and a rod receiving member carried by said car at each side of the pivotal support of said arm thereon, each member being adapted selectively to receive the end of said rod for positioning said arm with respect to said surface laterally of said car, said rod axially adjustable with respect to the engaged member for imparting a limited lateral movement to said arm when so positioned to shift the tool relatively to said surface.
